UNITED STATES PATENT OFFICE

PHILIP RETZ, OF NEW YORK, N. Y.

PENCIL POINTER AND CLEANER

Application filed November 14, 1930. Serial No. 495,704.

The invention has for an object to provide in convenient form means for pointing pencils and for cleaning the pencil points.

The invention also has as an object to provide a base having secured to one face a plurality of plies of an abrasive and to its other face a cleaning member.

Another object of the invention is to provide staples having their central portions at the cleaning member, the staples extending through the cleaning member, the base and the plurality of plies of the abrasive and with the central portions of the staples impressed into the cleaning member so that the resiliency of the cleaning member will take up the slack at the ends of the staples when one or more plies of the abrasive are removed after having been worn down in service.

Additional objects of the invention will appear in the following specification in which the preferred form of the invention is described.

In the drawings similar reference characters refer to similar parts in the several views, of which

Figure 1 is a perspective view illustrating the invention,

Figure 2 is an inverted plan view of the invention as illustrated in Figure 1, but on a larger scale, and

Figure 3 is a section view on the line 3—3 of Figure 1.

By referring to the drawings it will be seen that a base 10 is provided which is preferably made of white pine, the base being of any suitable design, but preferably having an opening or orifice 11 from which it may be hung on a hook, or which may be used to attach any other securing means.

At one face of the base 10 there is disposed a cleaner 12 which is preferably manufactured of felt, preferably a type of felt which will not retain the dust, but it will be understood that the cleaner may be manufactured of any other suitable material, although the cleaner should preferably be made of a material which may be compressed, as will be subsequently explained.

To the other face of the base 10 there is secured a plurality of plies of an abrasive

13, this abrasive 13 being preferably double-
art sand paper. Any desired number of plies
may be disposed above each other, as illus-
trated in Figures 1 and 3 of the drawings. It
is important that this sand paper, or other
abrasive 13, be secured to the base 10 under
all conditions, even when the base is hit
against a table or desk to free dust from the
cleaner 12 or the abrasives 13. It is also im-
portant that the abrasive 13 be secured to the
base by such means as will prevent the
abrasive from becoming free from the base
because of moisture in the atmosphere or
changes in temperature. To secure the
abrasive 13 to the base 10 in such a manner
as will meet all requirements, and also as a
means for securing the cleaner 12 to the base,
staples 14 are provided, these staples having
central portions 15 which are disposed at
the outer side of the cleaner 12 and which
may be impressed into the cleaner 12, as il-
lustrated in Figure 3. The ends 16 of the
staples 14 extend through openings 17 in the
cleaner 12, through openings 18 in the base
10 and through openings 19 in the plies of
abrasive 13. The terminals 20 of the staples
14 are then bent over the outer face of the
outer ply of abrasive 13.

It will be understood that one or more plies
of the abrasive 13 may be torn off and away
from the terminals 20 of the staples and that
the resiliency of the cleaner 12 will serve to
press the terminals 20 against the remaining
plies of abrasive 13, and it will also be under-
stood that when occasion requires the ter-
minals may be bent down against the remain-
ing plies of abrasive to hold the plies of
abrasive secured to the base 10.

What is claimed is:

1. In a pencil pointer and cleaner, a base, a resilient cleaner disposed at one side of the base, a plurality of plies of an abrasive disposed at the other side of the base, and securing means impressed in the cleaner, the securing means being disposed through the cleaner and the plies of abrasive and engag-
ing the outer side of the abrasive plies, the resiliency of the cleaner serving to hold the securing means to grip each ply of the abra- 100

sive as the next outer ply of the abrasive is removed.

2. In a pencil pointer and cleaner, a base, a felt cleaner disposed at one side of the base, a plurality of plies of an abrasive disposed at the other side of the base, and securing means impressed in the cleaner, the securing means being disposed through the cleaner and the plies of abrasive and engaging the outer side of the abrasive plies, the resiliency of the cleaner serving to hold the securing means to grip each ply of the abrasive as the next outer ply of the abrasive is removed.

3. In a pencil pointer and cleaner, a base, a resilient cleaner disposed at one face of the base, a plurality of plies of an abrasive disposed at the other face of the base, and a staple having its central portion impressed in the outer side of the cleaner, the ends of the staple extending through the cleaner, the base and the plies of abrasive and with their terminals bent over the outer abrasive ply, the resiliency of the cleaner serving to hold the securing means to grip each ply of the abrasive as the next outer ply of the abrasive is removed.

4. In a pencil pointer and cleaner, a base, a resilient compressible cleaner disposed at one face of the base, a plurality of plies of an abrasive disposed at the other face of the base, and securing means impressed in the cleaner, the securing means being disposed through the cleaner and the plies of abrasive and engaging the outer side of the abrasive and plies, the resiliency of the cleaner serving to hold the securing means to grip each ply of the abrasive as the next outer ply of the abrasive is removed.

5. In a pencil pointer and cleaner, a base, a resilient compressible cleaner disposed at one face of the base, a plurality of plies of abrasive disposed at the other face of the base, and a staple having its central portion impressed in the outer side of the cleaner, the ends of the staple extending through the cleaner, the base and the plies of abrasive and with their terminals bent over the outer abrasive ply.

6. In a pencil pointer and cleaner, a base, a felt cleaner at one face of the base, a plurality of plies of abrasive at the other face of the base, and a staple having its central portion impressed in the outer side of the cleaner, the ends of the staple extending through the cleaner, the base and the plies of abrasive and with their terminals bent over the outer abrasive ply, the resiliency of the cleaner serving to hold the securing means to grip each ply of the abrasive as the next outer ply of the abrasive is removed.

7. In a pencil pointer and cleaner, a base, a resilient compressible cleaner at one face of the base, a plurality of plies of abrasive at the other face of the base, two staples, each having its central portion at the outer side of the cleaner adjacent an end of the cleaner

with its ends extending through the cleaner, the base and the plies of abrasive, the terminals of the staples being bent over against the outer face of the outer ply of abrasive.

8. In a pencil pointer and cleaner, a base, a resilient cleaner disposed at one face of the base, a plurality of plies of abrasive at the other face of the base, two staples, each having its central portion impressed in the outer face of the cleaner, the ends of the staples extending through the cleaner, the base and the plies of abrasive and with the terminals of the staples bent over against the outer face of the outer ply of abrasive, the resiliency of the cleaner serving to hold the securing means to grip each ply of the abrasive as the next outer ply of the abrasive is removed.

9. In a pencil pointer and cleaner, a resilient cleaner, a plurality of plies of an abrasive, and a securing means impressed in the cleaner, the securing means engaging the outer side of the abrasive plies, the resiliency of the cleaner serving to hold the securing means to grip each ply of the abrasive as the next outer ply of the abrasive is removed.

10. In a pencil pointer and cleaner, a resilient compressible cleaner, a plurality of plies of an abrasive, and a staple impressed in the cleaner, the ends of the staple extending through the cleaner and the plies of abrasive and having their terminals bent over against the outer face of the outer ply of the abrasive.

Signed at New York city, in the county of New York and State of New York, this 13th day of November, A. D. 1930.

PHILIP RETZ.
